FUEL OIL FILTER CONSTRUCTION

Paul Williams and Frank W. Brazel, Detroit,
Mich., assignors to Skinner Purifiers Inc., De-
troit, Mich., a corporation of Delaware

Application June 5, 1936, Serial No. 83,754

4 Claims. (Cl. 210—184)

During the past few years there has been active interest in making internal-combustion engines in which the fuel is distributed to the cylinders by means of positive-pressure fuel-pumps, this principle being imperative in Diesel engines which depend upon the high-pressure pumps to force a predetermined quantity of fuel into the individual cylinders at the proper time for combustion.

10 Positive-pressure pumps are also used with the Hesselman type of engines wherein the fuel-oil is forced into the cylinders and ignited by spark-ignition, this style of construction having been used and likely to be employed to a larger extent 15 than at present on gasoline-engines in place of a carburetor.

The fuel-oil or gasoline, as the case may be, is pumped to the high-pressure plunger-pumps by means of a low-pressure pump, the latter merely 20 keeping the high-pressure pumps filled with the fuel.

Such high-pressure pumps force the fuel into the cylinders of the engine against the pressure of a small valve which has hundreds of pounds 25 of back pressure in order that it shall not open against the explosion of the mixture in the cylinder, but is opened by the pressure of fuel coming up to the valve.

These valves or injectors must have very close 30 clearances, and the high-pressure pumps require minute clearance as the pressures under which these pumps operate are about 5000 pounds to 7000 pounds liquid pressure, and if the moving parts had excessive clearances, the liquid would 35 be forced through them.

It has been found that when using these units the greatest difficulty in proper operation of the high-speed Diesel engines, which necessitate the employment of these excessively fine mechanisms, is the wear which is encountered from the small particles of carbon and flake mixture present in these fuels, such impurities being more prevalent in the heavier fuels, but, the lighter the fuel, the smaller the particles which would 45 cause difficulty.

The present invention, therefore, relates to improved filter-means which will positively and mechanically filter these oils or fuels to a sufficient fineness to insure the high-pressure pumps and nozzle parts against excessive wear; or, stated somewhat differently, this invention concerns certain features of betterment and advantage in filters, more particularly, but not necessarily exclusively or restrictedly, those of the so-called "streamline type", which are especially adapted for the employment in the relation specified.

One of the leading aims of the invention is to 50 provide a simple structure of this style which can

be easily and readily cleaned or flushed without interrupting the filtering operation.

Another object of the invention is to supply 5 a filter of this kind which is particularly adapted to filter the liquid fuel flowing to an internal-combustion engine, such character of filter being of particular advantage in cleaning the pumped fuel prior to its use in an internal-combustion engine of the fuel-injection design, using high-pressure pumps for forcing the fuel into the engine, it being apparent that such pumps must 10 be maintained free from injurious foreign matter to avoid damage due to the necessary snug fits of their moving parts.

A further purpose of the invention is to provide 15 a design of filter which can be flushed or cleaned without danger of admitting air into the fuel-system, this being a highly important characteristic of the novel filter.

To enable those acquainted with this art to 20 fully understand this invention and the benefits accruing from its employment, present preferred embodiments of the same have been illustrated in the accompanying drawings, forming a part 25 of the specification, and to which reference should be had in connection with the following detailed description, like reference numerals being employed in these drawings to designate the same parts.

Referring to these drawings:—

Figure 1 is a central, vertical section through 30 the improved filter construction;

Figure 2 is a horizontal section on line 2—2 of Figure 1;

Figure 3 is a partial end elevation and partial 35 vertical section of the construction;

Figure 4 is a fragmentary, enlarged section through one of the filter chambers;

Figure 5 illustrates a modified construction partially in elevation and partially in section; 40

Figure 6 is a detail section of one of the valves employed in the structure of Figure 5.

Referring first to the design or form of the filter presented in Figures 1 to 4, inclusive, it will be perceived that it comprises a casing or housing 45 divided into a number (in the present instance three) of compartments 10, 10 by upright, transverse or cross walls or partitions 12, 12, each such compartment being covered at its top end by a centrally-apertured disc 13, all three of 50 which are held down firmly on the top of the casing by an appropriate number of securing screws 14, 14.

Each such compartment or chamber accommodates one of the filter-packs 15, each composed 55 of a lower or bottom, metal disc 16 with a large number of superposed, registered, centrally-apertured or washer-like filter-discs 17, for example, made of paper charged or impregnated with a 60

material not soluble in the liquid to be filtered.

Internally each such filter-pack accommodates a long, coiled, contractile spring 18 secured in any approved manner at its lower end at 19 to the center of the corresponding end disc 16, the upper end of the spring having a terminal loop 21 occupying a peripheral groove in a short rod or cross-pin 22 resting or bearing on the top of the correlated cover 13 on opposite sides of the central aperture of the latter, such end loop of the spring being in the cover aperture referred to.

Thus these several springs hold the numerous discs 17 of their respective packs in firm contact or engagement with one another, the filtering action occurring between, rather than through, the paper discs.

Casing 11 is provided with a hollow cover 23 securely held thereon by a number of screws 24, 24, or in any other appropriate manner, a suitable 20 gasket 25 being interposed between the two elements 11 and 23 to make the joint pressure-tight, the casing in this manner being provided with an upper chamber 26 having an outlet pipe 27 connected to a high-pressure pump or pumps, shown 25 diagrammatically and supplied with the reference numeral 100.

At its lower part casing 11 has a single, inlet manifold-passage 28 in the casting forming the casing, such passage being intersected for each 30 of the three filter-stack compartments by a screw-threaded opening 29 communicating at its inner end with a small well 31 forming part of, or being directly connected to, the corresponding filter-pack compartment 10.

Each such opening or passage 29 accommodates the threaded shank 32 of a hollow valve-screw having an external, angular head 33, such shank or stem having a central, longitudinal passage 34 closed at its outer end and open at its inner end, 40 and having one or more lateral openings or ports 35 in register with, and communicating with, the manifold-passage 28 when the screw-valve is turned fully home as presented in Figure 3.

One end of the manifold-passage 28 is closed, 45 its companion opposite end being joined to a fuel-oil inlet-pipe connected to a low-pressure pump 101, the delivery pipe 27 being joined, as already explained above, to the high-pressure pump 100, which feeds the fuel for injection into 50 the cylinders of the internal-combustion engine, not shown.

The filter operates practically as follows:

Assuming that all of the three screw-threaded valves 32-33-34-35 are screwed fully home 55 in the position shown in Figure 3, so that the passage 28 is in direct connection with all three of the compartments 10 through the openings 35, 34, 31, the fuel-oil enters the manifold-passage 28, being delivered thereinto by the low-pressure 60 pump 101, flows through the three valves into the chambers 10, 10, passes between the paper-discs of the filter-packs into their interiors, from whence it flows into chamber 26 and then through the discharge-pipe 27 to the high-pressure 65 pumps which force it or inject it into the engine-cylinders at the proper moments.

In time, the exterior surfaces of the filter-packs become coated or overlaid with a stratum of filtered-out impurities which layer it is essential 70 shall be removed from time to time without interrupting the operation of the filter as a whole and without permitting the entrance of any air into the system, which, if it occurred, would seriously interfere with the efficient and proper 75 functioning of the associated engine.

This cleaning may be readily accomplished for the filter-packs individually, one at a time by causing a reverse flow of some of the cleaned oil through the filter-pack under consideration.

The screw-threaded valve 32-33, associated 5 with the filter-pack selected for cleaning, is turned by means of its head until its ports 35 have been shifted away from the passage 28 and are positioned outside of the casing or casting 11 for drainage purposes, as presented in Figure 10 4, the threaded stem 32 of the valve being sufficiently long to maintain the passage 28 closed.

Accordingly, now none of the impure or unfiltered oil can enter that particular filter-pack chamber and the pressure already inside of the 15 filter-pack, which is in direct connection with the chamber 26, forces oil out of the filter-pack between its discs into the chamber 10 from which it flows out through the connected passages 31, 34 and 35 from which it discharges into any sort 20 of a container or onto the ground or elsewhere.

The cross-section of the passages of the valve through which the drained-off oil flows is such that they are maintained full of the liquid for all of the period of such drainage, thus preventing any entrance of air into the system, this being an important consideration.

This inverse or opposite oil-flow through the filter-pack washes off the impurities from its outer surface and carries them down and along 30 with the oil which is discharged outside of the appliance in the manner stated.

While this cleaning or reverse flushing of one of the filter-packs is taking place, the normal 35 filtering operation is occurring continuously through the other packs, so that there is no interruption of proper, clean, fuel-oil feed to the engine.

When such filter-member has been sufficiently 40 flushed to clean or recondition it adequately, its valve is again screwed in until its ports 35 coincide with the passage 28, whereupon the normal or ordinary operation of that particular 45 section of the complete filtering-apparatus is again restored, drainage therefrom having been terminated just as soon as the ports 35 were inside of the casing.

As will be readily understood from what precedes and from the illustrations in the drawings, the valve-stem 32 is sufficiently long and the 50 filter-parts are so located and spaced, that the filter-pack is either in operation, or undergoing washing and drainage, or blocked against either of such actions when the ports 35 are closed by the walls of holes 29, the distance between passage 28 and the outside of the casing being such 55 as to keep the ports 35 closed, if desired, whereby that section of the filter-apparatus is inoperative, neither filtering nor cleaning then being accomplished.

After any one of the filter-elements has been 60 thus flushed or purged and again restored into operation, the other packs may be treated in the same way individually.

From what has been stated above it should 65 be clear that this improved filter construction consists of two or more separate compartments with one or more filter-packs in each of these compartments, the fuel-oil entering the unit from the low-pressure pump through the bottom inlet manifold, passing up around the filter-packs, between the discs thereof, up through the center 70 passages in the packs, and out of the top header, this operation leaving all of the solid impurities 75 on the outer surfaces of the filter-elements.

The low-pressure pump 101 is ordinarily maintained at some constant pressure, say thirty pounds or below, and this pump has a greater capacity than the high-pressure pumps to which it is feeding the fuel, the only purpose of the low-pressure pump being to be certain that the high-pressure pumps fill full of fuel at each stroke, as otherwise the fuel charge would not be of the right quantity.

10 Accordingly, the liquid fuel flows up through the filter and into the high-pressure pumps, and as it does so the solid impurities gradually build up on the exteriors of the filter-packs until the resistance to the fuel-flow becomes so great that 15 the filter cannot furnish sufficient fuel for the engine at high operating speeds.

Then, the operator idles the engine which causes the high-pressure pumps to require less fuel, and the pressure in the head or top of the 20 filtering apparatus builds higher if the fuel is not taken away from it as rapidly as the filter can perform its function.

Thereupon the operator opens one of the valves at the bottom of the filter which closes off the 25 low-pressure pump from that particular compartment of the apparatus and leaves the valve in the flushing position, so that the fuel can flow freely from such compartment.

The fuel pressure in the head or compartment 30 26 of the unit then washes the dirt off the filter by back or reverse flow therethrough and the fuel used for that purpose passes out onto the ground or into any appropriate container.

When the discharging liquid starts to show 35 clear the valve is closed and that filter-compartment has a clean filter-pack ready again for full production.

This operation is repeated for the various compartments of the filter unit, and in this manner 40 40 the operator is afforded an appliance which does not require frequent changes of filter-packs, does not need to be opened up for cleaning purposes, and can be successfully handled by the average operator, the filter being capable of being cleaned 45 on the road where operators have ordinarily heretofore been careless with respect to their preventative maintenance.

As has been stated, one outstanding distinct 50 advantage of the new construction is that by making the holes or passages in the valve of such size that the flowing out of the liquid fills these passages it is impossible for air to enter the system, and this is of paramount importance in the operation of fuel-pumps.

55 A modified style of structure is shown in Figures 5 and 6 and in this somewhat-different apparatus a plurality of casings or housings 36, 36 are used, two in this instance being shown, although a greater number may be availed of if desired.

Each of these casings contains a number of filter-packs 15, 15 of the same construction, and mounted in the same manner, as the packs already fully described, so that further reference 60 to their details of structure or mode of operation is not needed.

The tapered or conical-shaped bottom of each such casing or housing is connected by a short pipe 37 to one connection 38 of a three-way valve 70 39 which has a drain-pipe 41 joined to another of its connections 42, a third pipe 43 connecting at its opposite ends with the remaining connections 44, 44 of the two valves.

As is indicated in Figure 6, the plug or movable member 45 of each such valve has a straight

passage 46 through it and a branch passage 47 connected therewith, which construction permits a connection between the pipes 43 and 37 for admitting the fuel-oil into the casing, or allows a connection between pipes 37 and 41 for cleaning and drainage purposes, depending upon the position of the valves which may be operated by their handles.

A portion of pipe 43 between the two valves is joined by piping 48 to a low-pressure pump 49 10 which feeds the liquid to be treated into and through the filter-apparatus, which at its top has a pipe 51 joining together the two delivery or discharge ports or openings of the pair of casings, such pipe 51 being united to a high-pressure 15 pump 52 by a pipe 53.

As in the previous instance, the filtering elements or packs are arranged in parallel relation, that is to say, the two shells or housings 36, 36 and their filter-packs are in parallel relation as 20 distinguished from a series arrangement.

Assuming that the two valves 39, 39 are in such positions that the contents of the pipe 43 enters the bottom of both casings, the incoming fuel-oil, fed by the low-pressure pump 49, is 25 filtered in both casings at the same time through their contained filter-packs and is delivered to the high-pressure pump or pumps.

When it is desired to clean or flush the pack or 30 packs of either of the casings, its movable valve-plug is turned 90°, thereby connecting its pipe 37 to its drain-pipe 41, the other half of the filter-apparatus remaining in normal operation.

Obviously such turning of the valve effects a 35 reverse flow of oil through the corresponding filter-packs, the oil and its washed-off impurities passing out through the drain-pipe.

When the cleaning of such set of filter-packs has been completed, its valve 39 is turned back to normal position, thus reestablishing the regular 40 operation of that part of the appliance, and after such reinstatement, the other or companion filtering-means may be freed from accumulated foreign matter in the same manner.

Although only one high-pressure pump has 45 been illustrated diagrammatically in each instance, it will, of course, be understood that such a pump and its injector-nozzle is ordinarily employed for each cylinder of the engine, although a single low-pressure pump of appropriate capacity may be used to supply the fuel to all of the high-pressure pumps.

The invention as defined by the appended 50 claims is not necessarily limited and restricted to the precise and exact details of construction 55 presented nor to these particular embodiments, and more or less radical or minor changes may be incorporated in the constructions without departure from the heart and essence of the invention and without the loss of any of its substantial advantages.

We claim:

1. In a filter-apparatus, the combination of an inlet-conduit for the liquid to be filtered, a discharge-conduit for the filtered liquid, a plurality 65 of chambers connected to said inlet and discharge conduits in parallel relation to one another, a filtering-means in each of said chambers, a normally-closed drain for each of said chambers on the unfiltered liquid side of its filtering-means, 70 and means to suspend temporarily the feed of impure liquid from said inlet-conduit into any one of said chambers and to open the drain of said chamber, the drainage from said chamber effecting a reverse flow of filtered liquid through the 75

filtering-means of said temporarily-inoperative chamber, whereby the impurities adhering to the surface of said inactive filtering-means are washed away and carried off with the drained-off liquid, said inlet-conduit comprising a manifold common to all of said chambers and in which construction each of said means for suspending the feed of liquid to a chamber and for rendering the drain of said chamber operative comprises a 10 manually-operable valve occupying and movable longitudinally in an opening in the chamber-wall which communicates with the chamber and intersects said inlet-manifold, said valve having a longitudinal passage therein open at one end and 15 having a lateral port connecting with said passage, whereby when said valve is in one position said inlet-manifold is in communication with said chamber through said port and longitudinal passage and when said valve is in another position it closes such connection with said manifold and drains said chamber through said longitudinal passage and said port.

2. In a filter-apparatus, the combination of an inlet-conduit for the liquid to be filtered, a discharge-conduit for the filtered liquid, a plurality of chambers connected to said inlet and discharge conduits in parallel relation to one another, a filtering-means in each of said chambers, a normally-closed drain for each of said chambers on the unfiltered liquid side of its filtering-means, and means to suspend temporarily the feed of impure liquid from said inlet-conduit into any one of said chambers and to open the drain of said chamber, the drainage from said chamber 25 effecting a reverse flow of filtered liquid through the filtering-means of said temporarily-inoperative chamber, whereby the impurities adhering to the surface of said inactive filtering-means are washed away and carried off with the drained-off 30 liquid, and in which construction each of said drains is of such capacity that when it is in operation the discharge of liquid therethrough prevents air entering the system through such drain, and in which said inlet-conduit comprises a manifold common to all of said chambers and in which each of said means for suspending the feed of liquid to a chamber and for rendering the drain of said chamber operative comprises a manually-operable valve occupying and movable longitudinally in an opening in the chamber-wall which 35 communicates with the chamber and intersects said inlet-manifold, said valve having a longitudinal passage therein open at one end and having a lateral port connecting with said passage, 40 whereby when said valve is in one position said inlet-manifold is in communication with said chamber through said port and longitudinal passage and when said valve is in another position it closes such connection with said manifold and drains said chamber through said longitudinal passage and said port.

3. In a filter-apparatus, the combination of an inlet-conduit for the liquid to be filtered, a discharge-conduit for the filtered liquid, a plurality of chambers connected to said inlet and discharge conduits in parallel relation to one another, a filtering-means in each of said chambers, a normally-closed drain for each of said chambers on the unfiltered liquid side of its filtering-means, and means to suspend temporarily the feed of impure liquid from said inlet-conduit into any 45 one of said chambers and to open the drain of said chamber, the drainage from said chamber effecting a reverse flow of filtered liquid through

the filtering-means of said temporarily-inoperative chamber, whereby the impurities adhering to the surface of said inactive filtering-means are washed away and carried off with the drained-off liquid, said construction being in combination with a pump to feed the impure liquid through said inlet-conduit into said chambers and pump-means acting at a higher pressure than that of said pump operating on the purified liquid delivered to it through said discharge-conduit, and 5 in which structure said inlet-conduit comprises a manifold common to all of said chambers and in which each of said means for suspending the feed of liquid to a chamber and for rendering the drain of said chamber operative comprises a manually-operable valve occupying and movable longitudinally in an opening in the chamber-wall which communicates with the chamber and intersects said inlet-manifold, said valve having a longitudinal passage therein open at 10 one end and having a lateral port connecting with said passage, whereby when said valve is in one position said inlet-manifold is in communication with said chamber through said port and longitudinal passage and when said valve is in another position it closes such connection with said manifold and drains said chamber through said longitudinal passage and said port.

4. In a filter-apparatus, the combination of an inlet-conduit for the liquid to be filtered, a discharge-conduit for the filtered liquid, a plurality of chambers connected to said inlet and discharge conduits in parallel relation to one another, a filtering-means in each of said chambers, a normally-closed drain for each of said chambers on the unfiltered liquid side of its filtering-means, and means to suspend temporarily the feed of impure liquid from said inlet-conduit into any one of said chambers and to open the drain of said chamber, the drainage 25 from said chamber effecting a reverse flow of filtered liquid through the filtering-means of said temporarily-inoperative chamber, whereby the impurities adhering to the surface of said inactive filtering-means are washed away and 30 carried off with the drained-off liquid, and in which construction each of said filtering-means comprises a series of centrally-apertured, superposed, registered discs substantially impervious to the liquid being filtered and held pressed together, whereby the filtering action occurs between the discs, the liquid undergoing the filtering operation passing inwardly between said discs, and in which structure said inlet-conduit 35 comprises a manifold common to all of said chambers and in which each of said means for suspending the feed of liquid to a chamber and for rendering the drain of said chamber operative comprises a manually-operable screw-threaded valve occupying a screw-threaded opening in the chamber-wall which communicates with the chamber and intersects said inlet-manifold, said valve having a longitudinal passage 40 therein open at one end and having a lateral port connected with said passage, whereby when said valve is in one position said inlet-manifold is in communication with said chamber through said port and longitudinal passage and when said valve is in another position it closes such connection with said manifold and drains said chamber 45 through said longitudinal passage and said port.
